Specification for Design.

Patented May 4, 1920.

Application filed October 11, 1919. Serial No. 330,156. Term of patent 3½ years.

To all whom it may concern:

Be it known that I, JOHN P. STETSON, a citizen of the United States, and a resident of the borough of Manhattan, in the county, city, and State of New York, have invented a new, original, and ornamental Design for Display-Stands, of which the following is a specification, reference being had to the accompanying drawing, forming a part thereof.

In the said drawing:—

Figure I is a perspective front view of a display-stand, showing my new design; and

Fig. II is a similar rear view of the same.
I claim:—

The ornamental design for a display stand as shown.

In testimony whereof I have signed my name to this specification in the presence of two subscribing witnesses.

JOHN P. STETSON.
